US0D1111458S

(12) United States Design Patent (10) Patent No.: US D1,111,458 S
(45) Date of Patent: * Feb. 10, 2026

(54) ROTATING COSMETIC ORGANIZER

(71) Applicant: Pingtan Laike Trade Co., Ltd, Fuzhou (CN)

(72) Inventor: Jiaying Ye, Nanping (CN)

(73) Assignee: Pingtan Laike Trade Co., Ltd., Fuzhou (CN)

() Term: 15 Years

(21) Appl. No.: 29/944,753

(22) Filed: May 30, 2024

(51) LOC (15) Cl. 06-04

(52) U.S. Cl.

USPC D6/677.1; D7/501
